SUPERREGENERATIVE RECEIVER SYSTEM

Lewis F. Jaggi, San Antonio, Tex.

Application March 12, 1945, Serial No. 582,380

2 Claims. (Cl. 250—20)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to radio receivers and more particularly to an improved wide band panoramic receiver employing superregenerative detection.

Panoramic receivers of older design have been characterized by limitations in sensitivity and in breadth of frequency response.

The objects of the present invention comprise the provision of an improved panoramic receiver that minimizes the limitations in sensitivity and in breadth of frequency response which have been objectionable characteristics of the older receivers; and the provision of a panoramic receiver that uses superregenerative detection in its operation and wherein a plurality of superregenerative detectors are effectually prevented from causing mutual interference with respect to each other in covering supplemental or the same frequency ranges and operating from a common quench oscillator.

Further objects of my invention are to provide means which will permit the operation of multiple band panoramic receivers without interference with one another. It is also an object of my invention to provide means for permitting two normal panoramic receivers that are tuned to neighboring frequencies, or to the same frequency, each to receive signal without the interference that would normally be present due to the strong radiated signal from such receivers.

It is a further object of my invention to provide means whereby a superregenerative receiver and a transmitting oscillator may rapidly alternate in operation without mutual interference.

With the above and other objects in view which will be apparent to those who are informed in the field of radio circuits from the following description, an illustrative circuit for the present radio receiver invention is shown in schematic form in the accompanying drawings, wherein:

Fig. 1 is a circuit diagram of a superregenerative panoramic receiver of two bands; and

Fig. 2 is a circuit diagram of a device that embodies the present invention and that comprises a pair of superregenerative receivers that may be tuned independently of each other.

A circuit for a panoramic receiver that embodies the present invention is shown in schematic form in Fig. 1 of the accompanying drawings and is adapted for covering a desired broad range of frequencies by suitable means, such as by

2

the use of at least two receiving detectors 1 and 2 that are of supplemental frequency ranges. Suitable means, such as a quench frequency oscillator 3, or the like, is provided in the circuit. 5 This oscillator 3, in addition to its normal function is adapted for substantially preventing harmonics in the outputs from the lower range receiving detector from interfering with the proper functioning of the upper frequency range detector end of the panoramic receiver. The oscillator 3 also prevents interference between the detectors 1 and 2 if they are tuned to the same frequency at any time.

The receiving detector 1 may be assumed to be 10 a low frequency range detector. The receiving detector 2 may be assumed also to have a frequency range that is higher than the frequency range of the detector 1 and as having a lower limit which overlaps the upper limit of the frequency range of the detector 1 so that within the overlapping range the detectors 1 and 2 are both tuned to the same frequency. The combined ranges of the receiving detectors 1 and 2 provide the total range of the panoramic receiver that is contemplated hereby. The separate push-pull quench frequency oscillator 3 serves effectually to minimize or to prevent the harmonics of the low range detector 1 from interfering with the operation of the high range detector 2 by exciting the 15 two detectors 1 and 2 alternately thru the use in rapid succession of alternate half cycles from the quenching voltage. The separate push-pull quench frequency oscillator 3 also serves to prevent interference between the detectors 1 and 2 when tuned to the same or neighboring frequencies.

The two receiving detectors 1 and 2 are usual 20 forms of superregenerative detectors and are provided with individual antennas 4 and 5, respectively, by means of which intercepted signals are fed to the detectors 1 and 2. The push-pull oscillator 3 is also of usual form and provides an externally supplied quench signal to the detectors 1 and 2.

Individual panoramic sweeps for the detectors 1 and 2 are provided in any desired manner, as by being covered by the rotatable continuously variable capacitors 6 and 7, respectively, that are disposed therein. The variable capacitors 6 and 25 7 are synchronized with each other in any desired manner, as by being driven mechanically by a common motor 8, as indicated by dotted lines that extend therebetween. In a satisfactorily functioning illustrative model of the device the rate of rotation that was maintained for the

variable capacitors 6 and 7 was approximately 1200 revolutions per minute.

The resonant circuit that is associated with the capacitor 6 covers the low frequency range as the panoramic sweep of the detector 1, and the resonant circuit that is shown with the capacitor 7 covers the high frequency range of the panoramic sweep of the detector 2.

The output terminals 9 and 10, from the low range detector 1 apply signal to a suitable reproducer or signal presentation device, such as an oscilloscope 11, or the like. The output terminals 12 and 13, from the high range detector 2, apply signal to another reproducer or oscilloscope 14. The two oscilloscopes 11 and 14 are connected to a sweep voltage generator 15. The sweep voltage generator 15 is driven by the motor 8, as indicated by a dotted line that extends therebetween. The time base of the oscilloscopes 11 and 14 and the frequency sweeps of the superregenerative detectors 1 and 2 are synchronized by operation of the common motor 8.

In operation, a signal that is intercepted by the antenna 4 and that is received by the low range detector 1 in its panoramic sweep, is applied as pulses of direct current thru the output terminals 9 and 10 therefrom on the signal plates of a cathode ray tube within the oscilloscope 11, on the screen of which the signal pulse appears at a definite frequency reading as a pip that extends from the ground line thereon. The panoramic sweep of the receiver 1 is covered by the rotating variable capacitor 6 that is driven by the motor 8.

A signal that is intercepted by the antenna 5 and is received by the high range detector 2, as its condenser 7 sweeps thru its frequency range, is applied as pulses of direct current thru the output terminals 12 and 13 therefrom to the signal plates of a cathode ray tube part of the oscilloscope 14, on the screen of which the signal pulse appears as a pip that extends from the ground line thereupon at a definite frequency reading that corresponds to the signal frequency on the cathode ray tube screen. The panoramic sweep of the receiver 2 is covered by the rotating variable capacitor 7 that is driven by the motor 8. The frequency sweeps of the superregenerative detectors 1 and 2 and the time bases of the oscilloscopes 11 and 14 are all synchronized since the variable capacitors 6 and 7 and the sweep voltage generator 15 are driven in common by the motor 8.

The quench signal that is developed by the push-pull oscillator 3 appears across the terminals 16 and 17 as an alternating voltage that is balanced to ground and that is superimposed upon the positive direct plate supply voltage for the detector 1 and the detector 2. The plate voltage and the quench signal for the low range detector 1 are supplied from the terminal 16. The plate voltage and the quench signal for the high range detector 2 are supplied from the terminal 17. In both cases return is through ground. For receiving signals of fifty megacycles frequency and above, it has been determined experimentally that a quench frequency of one hundred kilocycles operates satisfactorily.

During the half cycle within which the quench frequency signal on the terminal 16 is negative, the low frequency range detector 1 is quenched and no regenerative detection takes place. During this same half cycle, the quench frequency signal on the terminal 17 is positive and the higher frequency range detector 2 will regeneratively

detect any received signal that appears upon the frequency channel to which the detector 2 is then momentarily tuned. A group of pulses is formed the pulse repetition rate of which is the quench frequency. The envelope of the group of pulses constitutes the pulse that is presented at the terminals 12 and 13 of the high frequency range detector 2. Due to the rapid rotation of the capacitor 7, the detector 2 tunes to any received signal momentarily and the duration of the pulse corresponding to the signal is very short.

Since the quench voltage appears in opposite phase upon the two detectors 1 and 2, the two detectors are not at any time active simultaneously and one of the detectors is prevented from picking up the oscillations of the other detector. In the absence of this provision, any oscillations in the lower frequency range detector 1 would put out upper harmonics, or for that matter fundamentals, that might fall within the detection range of the upper frequency range detector 2. These harmonics would be detected by the detector 2 and would appear as indications of external signals received. These harmonics signals would, in fact, be false signals since they would originate within the circuit. By causing the quench frequency to alternate between the two detectors 1 and 2, as provided hereby, each detector is active over time intervals of the same length and for as much of the time as the other detector were not present.

Two normal superregenerative receivers 18 and 19 which receive their quench signals in push-pull from quench oscillator 3 are shown in Fig. 2 of the drawings.

The circuit that is shown in Fig. 2 differs from that shown in Fig. 1 in that receivers 18 and 19 are single-signal receivers and not panoramic receivers as are the receivers 1 and 2. Each receiver 18 and 19 may be tuned independently of the other to a selected signal, either each to a different signal or both to the same signal.

Each receiver 18 and 19 is shown with its own adjustable B voltage supply 20 and 21, respectively. The receivers 18 and 19 are fed quench signal output from an oscillator 22 thru the condensers 23 and 24, respectively. Signal is intercepted and fed to the receiver 18 by the antenna 25 and to the receiver 19 by the antenna 26.

The operation of the device that is shown in Fig. 2 is similar to that which has been explained for the circuit that is shown in Fig. 1.

The quench voltage that is fed from the oscillator 22 to the receivers 18 and 19 is made to serve a useful purpose in both phases of its cycle. In one half of the quench voltage cycle the receiver 18 is receiving and the receiver 19 is blocked. In the other half of the quench voltage cycle the receiver 19 is receiving and the receiver 18 is blocked. There is no interference with the reception of signal by one receiver due to the oscillation of the other receiver.

The circuit of the receiver 19 may equally well be considered to represent a transmitting oscillator. In this case, due to the alternations of the blocking action by the quench oscillator 3, the receiver 18 continues to receive right through a transmission of the receiver 19 considered as a transmitter.

It will be noted that in conformity with the teachings of the present invention, a superregenerative detector would not hear even an extremely high powered oscillator when quenched in the manner that is described herein. The high power quenched oscillator can then

serve as a radio interfering transmitter and an observer can listen to signal thru the operations of the oscillator by the use of quench phasing between the detectors or receivers. When so used, the quenched oscillator serves as a super-regenerative circuit where only the radiation is used rather than where it is used as a detector. The quenched oscillator may be extremely high powered and may radiate considerable energy when it is not operating in the quenched portion 10 of the cycle.

It is to be understood that the particular circuits and the particular parts and components that have been shown and described herein have been submitted for the purposes of illustrating and explaining satisfactorily operating embodiments of the present invention, and that modifications, alterations and substitutions that result in satisfactory devices may be made therein without departing from the present invention as defined by the appended claims.

What I claim is:

1. A panoramic receiver system, comprising in combination a low frequency range superregenerative detector, a high frequency range superregenerative detector supplementing the range of the low frequency range detector, a presentation device for said low frequency range detector, a presentation device for said high frequency range detector, a sweep voltage generator serving both of said presentation devices, a motor synchronously providing a time base for the two

5 presentation devices and frequency sweep for the two detectors, and a quench oscillator for alternately quenching said detectors.

2. A panoramic receiver system comprising in combination a pair of superregenerative detectors having variable tuning means for respectively tuning said receivers over contiguous frequency ranges, means for simultaneously sweep- 15 ing said tuning means over said frequency ranges, means for alternately quenching said detectors whereby interference therebetween is avoided, indicator means for simultaneously presenting the outputs of said detectors, and means for providing a time base for said indicator means synchronously with the frequency sweep of said detectors.
